UNITED STATES PATENT OFFICE.

HARRY STEVENS, OF CHESLEY, ONTARIO, CANADA.

CLOTHES-DRIER.

1,159,606.

Specification of Letters Patent.

Patented Nov. 9, 1915.

Application filed February 8, 1915. Serial No. 6,939.

To all whom it may concern:

Be it known that I, HARRY STEVENS, a subject of the King of Great Britain, of the town of Chesley, county of Bruce, Province 5 of Ontario, Canada, have invented certain new and useful Improvements in Clothes-Driers, of which the following is a specification.

My invention relates to improvements in 10 clothes driers, and the principal object of my invention is to provide suitable supporting means for the supporting arms for the clothes to lock them in operative position, and further to provide means whereby the 15 supporting member for the supporting arms may be readily coupled to and uncoupled from the standard for said supporting members.

The construction of my invention will be 20 hereinafter particularly set forth and what I claim as new will be pointed out in the claim forming part of this specification.

Figure 1 is a side elevation of my clothes drier, showing the supporting arms there- 25 for held in operative position, certain parts being broken away and shown in section for clearness of illustration. Fig. 2 is a plan view of the clothes drier with portions of the supporting arms shown in operative po- 30 sition, and Fig. 3 is a detail view, showing partly in section the spring-provided hinge associated with the prop and its supporting member.

In the drawings, like characters of refer- 35 ence indicate corresponding parts in each figure.

A is any suitable standard which is de- 40 signed to be secured after any suitable manner to any suitable supporting means (not shown) such as a wall. The said standard A is rabbeted so as to provide longitudinal inner grooves B and the supporting member C is provided with side ribs D which op- 45 erate within the grooves B. The outer face E of the member C projects beyond the outer face F of the standard A and through the longitudinal slot G formed in said outer face F. The construction just described is of course well known, and it permits the 50 supporting member C to be moved up and down within the standard A.

In order to support the supporting mem- 55 ber C in any desired position in respect of the standard A, I provide a resilient metal plate H secured by any suitable means such

as screws I at its upper end to the supporting member C. The lower end J of the plate H extends underneath the lower end K of the supporting member C, and performs the function of a bolt, in that its inner end L is designed to rest within any desired one of the plurality of pockets M formed in the inner face N of the standard A. In the position of the metal plate H illustrated in Fig. 1, the supporting member C is coupled to the standard A. By pulling outward on the hand grip O carried by the metal plate H, the end L is withdrawn from the pocket M it is resting in, and then the supporting member C may be raised or lowered as required into a new position. Since the extremity of the end L is always in contact with some portion of the standard A, the metal plate H is always under strain, thus insuring that the said plate will effectually couple the supporting member C to the standard A and prevent the accidental movement of said supporting member.

Secured to the upper end of the supporting member C and against the outer face E thereof is a plate 2, which is considerably wider than the standard A.

3 is a plate which is hinged by any suitable means such as hinges 4 (one only of which is shown) to the plate 2.

5 is a plate spaced apart from the plate 3 by a plurality of supporting arms which are positioned between these plates and pivoted thereto by means of any suitable means such as screws 7, which screws also secure 90 said plates 3 and 5 together. The clothes are designed to be thrown over the supporting arms 6 in the usual manner.

In order to support the supporting arms 6 in operative position, I provide a prop 8 which is coupled to the front portion of the plate 3 by a suitable spring-provided butt hinge 9. The lower end of the prop 8 rests in the bottom of a pocket 10 formed in the outer face E of the supporting member C, 100 and in this position the said prop holds the supporting arms 6 and the connected parts in the position illustrated by full lines in Fig. 1. In order to prevent the accidental displacement of the prop 8 from the pocket 10, I mount around the pintle 11 of the butt-hinge 9 a spring 12, one end 13 of which is held in a pocket 14 formed in the underside of the plate 3. The said end 13 of the spring is retained in place by the leaf 15 of the 105 110

hinge 9. The other end 16 of the spring 9 is also held in a pocket 17 formed in the inner side of the prop 8 at its upper end, and is retained in place by the leaf 18 of 5 the said spring. Any suitable means such as screws 19 are used to couple the leaves of the said hinge 9 to their supporting members. The spring 12 is so constructed that were it unmounted it will exert energy to 10 move the ends 13 and 16 toward each other, and it will therefore be understood that the action of the spring 12 will be to exert energy to retain the prop 8 in the position illustrated in full lines in Fig. 1, for the 15 purpose set forth.

By removing the prop 8 from the pocket 10, the said prop together with the supporting arms 6 and the plates 3 and 5 can be folded to occupy substantially the dotted 20 position illustrated in Fig. 1.

From the foregoing specification it will be understood that my clothes drier while very strongly built, and consequently durable, is at the same time manufactured at a low cost 25 so as to permit an article of this class to be marketed at a low figure and still provide a reasonable profit.

Carried by the standard A and to one side thereof projecting beyond the outer face F

is a stop *a* which is designed to limit the 30 downward movement of the plate 2.

What I claim as my invention is:

In a clothes drier, the combination with a supporting member provided in its outer face with a pocket; a pair of plates; means 35 whereby said plates are hinged to said supporting member, and a plurality of supporting arms positioned between said plates and pivoted thereto at their inner ends, of a prop; a butt hinge, one leaf of which is secured to the underside of the lowermost of said plates and the other leaf of which is secured to the inner side of the upper end of said prop; the pintle coupling said leaves together, and a spring mounted on said pintle, one end of said spring being coupled to the said lowermost plate, and the other end of said spring being coupled to the other end of said prop, the said spring exerting energy 40 to retain the lower end of said prop in said pocket when said supporting arms are held in operative position.

In testimony whereof I have affixed my signature in presence of two witnesses.

HARRY STEVENS.
